(57) **CLAIM**

The ornamental design for a rotatable furniture pull handle, as shown and described.

DESCRIPTION

FIG. 1 is a perspective view, looking from above, of a rotatable furniture pull handle showing my new design;

FIG. 2 is a first side elevation view thereof;

FIG. 3 is the opposite side elevation view thereof;

FIG. 4 is a top plan view thereof;

FIG. 5 is a bottom plan view thereof; and,

FIG. 6 is a first end elevation view thereof, the opposite end elevation view being a mirror image thereof.
